Charles D. Gooding, Atty.

UNITED STATES PATENT OFFICE

GEORGE W. CAVERLY, OF BOSTON, MASSACHUSETTS, ASSIGNOR TO JOSEPH S. WATERMAN & SONS INC., OF BOSTON, MASSACHUSETTS, A CORPORATION OF MASSACHUSETTS

FOLDING SUPPORT

Application filed May 27, 1930. Serial No. 455,993.

This invention relates to a folding support and particularly to a type of support that is adapted to support a casket.

The object of the invention is to provide a support of light, strong and simple construction which, when in an open position, may be utilized as a support for caskets and which, when not in use, may be easily and quickly collapsed and folded to occupy a minimum amount of space.

Another object of the invention is to provide a means for automatically locking the top members of the support in their open position when the support is moved from its folded to its open position, thereafter making it impossible for the support to collapse without first actuating the locking means to unlock the top members.

Another object of the invention is to provide diagonally positioned bracing means for the lower portion of the support, said bracing means being actuated automatically to "break" the bracing effect when the adjacent abutting portions of the top members are moved upwardly in folding the support.

The invention consists in a support as set forth in the following specification and particularly as pointed out in the claims thereof.

Referring to the drawings:

Fig. 1 represents a front elevation of a support embodying my invention, said support being located in its open position.

Fig. 2 is a side elevation of the support.

Fig. 3 is a front elevation illustrating the support in its collapsed or folded position.

Fig. 4 is a detail sectional view illustrating the manner in which the operating rod for the diagonal braces is connected to one of the top members.

Fig. 5 is a detail sectional elevation illustrating the locking means for the top members.

Like numerals refer to like parts throughout the several views of the drawings.

In the drawings, 6 represents the side frames of the support, each of said frames being preferably constructed in a single piece of cast aluminum. Pivottally attached to each side frame 6 at the top thereof is a top member 7 also constructed in a single piece

of cast aluminum. The top members 7 have ears 8 formed integral therewith, which co-operate with ears 9 formed integral with the frames 6 and said ears are connected together by means of a pivotal pin 10. The ears 8 and 9 are so positioned upon the top members 7 and side frames 6 respectively that when the top members are located in their open position that they will rest in a horizontal position with their lower edges supported upon the top edge of the frame 6.

The top members 7 are pivotally attached one to another at the center of the support by means of pivotal pins 11 which project through co-operating ears 12 which are provided upon the top members. The side frames 6 are strongly braced adjacent to the bottom thereof by a plurality of braces 13, of which there are four in number, positioned diagonally. One end of each brace 13 is pivotally attached at 14 to a corner portion of the frame 6 and all of the braces are pivotally attached together at 15, the pivotal point being located in a transverse plane which passes through the center of the support and which also includes the pivots 11 of the top members 7. The braces 13 are operatively connected to one of the top members 7 by means of a rod 16, the lower end of which is coaxially pivoted at 15 to the inner ends of the braces 13. At its upper end the rod 16 is pivotally attached at 17 to an ear 18 which is formed integral with one of the top members 7 and the axis of the pivot 17 is co-axial with the axes of the pivots 11 of the top members 7.

The mechanism for automatically locking the top members 7 in their open position thereby holding the entire support in its open position is as follows:—Located upon each side of one of the top members 7 is a catch 19 embodying therein a notched finger 20 which projects through oppositely disposed aligning openings 21 provided in the top members 7, and each notched finger 20 is adapted to be engaged by a latch 22 which is pivotally attached at 23 to the other top member 7. The latch 22 has a notched portion 24 formed integral therewith which cooperates with the notched finger 20 in secur-

ing the latch 22 to the catch 19, and a flat spring 25 which is attached to one of the ears 12 engages the latch 22 in a manner to normally hold the notched portion 24 of the latch 22 in engagement with the notched finger 20 of the catch 19.

The supports of this invention are used in pairs, each support being inserted beneath an end portion of a casket and both of these supports are held spaced apart by any suitable form of spacing means, and when the supports are located in their open position, the top members 7 are locked securely together by the locking mechanism and when said top members are so locked the lower portions of the side frames 6 are effectively braced and it is impossible to "break" the pivotal connection 15 by means of which the brace members 13 are joined together.

When it is desired to collapse the support and fold the same into the position illustrated in Fig. 3, the latches 22 are actuated against the tension of the springs 25 and the notched portions 24 of said latches are disengaged

from the notched fingers 20 of the catches 19. The adjacent abutting portions of the top members 7 are then grasped and pulled upwardly, pulling the rod 16 upwardly and "breaking" the pivotal joint 15 which connects the braces 13 together, and a continued upward movement of the adjacent portions of the top members 11 will cause all of the parts to be folded into the position illustrated in Fig. 3.

When the support is moved from its folded to its open position, as the adjacent portions of the top members 7 close toward each other, the curved extremity of the notched finger 20 engages the curved extremity of the notched portion 24 of the latch 22 and the latter will yield sufficiently upon its pivot 23 to allow the notched finger 20 to pass beyond the extremity of the notched portion 24 and the spring 25 will finally move the latch 22 to cause the portion 24 thereof to interlock with the portion 20 of the catch. It will then be impossible to again collapse the support until the locking means is again actuated.

I claim:

1. A folding support for caskets and the like comprising two side frames, two top frames of like dimensions pivotally connected to one another along their inner edges and to the upper ends of the side frames at their outer edges, diagonal bracing members pivotally connected adjacent the lower ends of the side frames and at opposite sides thereof, and pivotally joined intermediate the side frames at a common meeting point, and a rod interconnecting the diagonal braces and top members at their pivotal axes to cause the top members and braces to move in unison when the support is opened or closed.

2. A folding support for caskets and the

like comprising two side frames, two top frames of like dimensions pivotally connected to one another along their inner edges and to the upper ends of the side frames at their outer edges, diagonal bracing members pivotally connected adjacent the lower ends of the side frames and at opposite sides thereof, and pivotally joined intermediate the side frames at a common meeting point, a rod interconnecting the diagonal braces and top members at their pivotal axes to cause the top members and braces to move in unison when the support is opened or closed, and cooperating latches mounted adjacent the meeting edges of the top members and yielding urged to cooperative position to automatically lock the top members when the support is in open position.

In testimony whereof I have hereunto set my hand.

GEORGE W. CAVERLY.
